UNITED STATES PATENT OFFICE

163,022

TOY SWORD

Donald W. Brooks, Oradell, N. J.

Application December 30, 1949, Serial No. 6,930

Term of patent 14 years

(Cl. D34—15)

To all whom it may concern:

Be it known that I, Donald W. Brooks, a citizen of the United States, residing at Oradell, county of Bergen, and State of New Jersey, have invented a new, original, and ornamental Design for a Toy Sword, of which the following is a specification, reference being had to the accompanying drawing, forming part thereof.

Figure 1 is a perspective view of the toy sword, showing my new design;

Fig. 2 is a side view thereof, to a reduced scale; and

Fig. 3 is an edge view thereof, to a reduced scale.

The beaded chain has been partially broken away in Fig. 2 for convenience of illustration.

I claim:

The ornamental design for a toy sword, substantially as shown and described.

DONALD W. BROOKS.
